GILBERT MURPHY AND WALTER A. SIMOND, OF FRANKLIN, NEW HAMPSHIRE,
ASSIGNORS TO ACME KNITTING MACHINE & NEEDLE COMPANY, OF FRANKLIN,
NEW HAMPSHIRE, A CORPORATION OF NEW HAMPSHIRE

THREAD-FEEDING MECHANISM FOR KNITTING MACHINES

Application filed April 13, 1921. Serial No. 460,958.

- This invention relates to hosiery knitting machines and is especially concerned with the thread feeding mechanism of machines of this type.
- 5 It has been proposed heretofore to provide hosiery knitting machines with automatic mechanism for reinforcing the heel and toe of a stocking, and also for reinforcing certain other parts of the stocking.
- 10 The present invention, however, aims to improve both the reinforcing means and also the mechanism that controls this means with a view particularly to simplifying such constructions, improving their reliability, and 15 reducing their cost of manufacture.

The nature of the invention will be readily understood from the following description when read in connection with the accompanying drawings, and the novel features will be particularly pointed out in the appended claims.

Referring now to the accompanying drawings,

25 Figure 1 is a side elevation of a knitting machine embodying the features of the present invention, certain parts of the machine being omitted for the sake of clearness;

Fig. 2 is a front elevation of a portion of the operating mechanism of the machine 30 shown in Fig. 1;

Fig. 3 is a rear elevation of certain parts of the machine with which the features of the present invention are more particularly concerned;

35 Fig. 4 is a side elevation of the twister mechanism at the head of the machine;

Fig. 5 is a perspective view showing a detail of the mechanism shown in Fig. 4; and

40 Fig. 6 is a view of the opposite side of the mechanism shown in Fig. 4.

The drawings illustrate the features of the present invention as embodied in a machine constructed substantially in accordance with the Hemphill Patent No. 629,503, granted July 25, 1899, although the machine illustrated includes modifications of the Hemphill machine which enable it to knit either plain or ribbed fabrics and to change automatically from one of said styles of

knitting to the other. Consequently, this machine is adapted to knit hosiery in which the heel and toe are fashioned and which has a ribbed cuff or leg. So far as the features of the present invention are concerned, 55 however, the mechanism added to the Hemphill machine to enable the ribbing operation to be performed need not be described.

Reference should be made to the Hemphill patent above designated for a complete 60 understanding of the driving and controlling mechanisms of the machine shown; but a brief description of certain features of this machine will be given here, the parts referred to being designated by the reference characters used for them in the Hemphill patent.

For present purposes it is sufficient to state that the machine shown comprises a main driving shaft 7, Fig. 2, which is driven through suitable connections with high and low speed pulley 10^a and 10, respectively. The machine also includes a cam shaft 30 that is driven through a pawl and ratchet mechanism under the control of the pattern chain 35, and this shaft carries certain of the cams through which the sequence of operations of the machine is controlled. The needle cylinder is mounted at the head of the machine, as will readily be understood by those skilled in this art, and is held in a stationary position while the cams that operate the needles rotate around it. Usually this cam mechanism rotates continuously, but in fashioning the heel and toe the cams 75 are given a rotary reciprocating movement.

For this purpose also half the needles are thrown out of action at the beginning of the heel and toe knitting operations and this operation is produced by a cam 171, Figs. 1 and 2, carrying cam members 173^a and 173^b which engage with the end of a bell crank lever 156 mounted on a stub shaft 26. Normally this lever is held in the position in which it is shown in Fig. 1 but when it is 95 acted upon by one of the cams on the cam wheel 171 it is tipped in a clockwise direction for the purpose above mentioned. Because of the functions performed by the cam 171 and the bell crank lever 156, these 100

parts are commonly referred to, respectively, as the heel and toe cam and the heel and toe lever.

According to the present invention this mechanism is utilized in controlling certain functions of the thread reinforcing or twister mechanism. For this purpose the rear arm of the lever 156 is drilled to receive two links 105 and 106, Fig. 3, the link 105 being 5 pivotally connected at its lower end to one arm of a lever 107 fulcrumed at 108 on the frame 2, and the link 106 being similarly connected to one arm of a lever 109 fulcrumed at 110 on the frame. The opposite 10 arms of the lever 107 and 109 are connected, respectively, to the lower ends of vertical rods 111 and 112. The links 105 and 106 have their upper end portions threaded to receive nuts 113 and 114, respectively, and 15 when the rear arm of the lever 156 is swung upwardly by the engagement of the forward arm of said lever with one of the cams on the cam wheel 171, this movement is transmitted through the connections just described to the rod 111 and link 112 pulling them downwardly.

A twister mechanism or thread reinforcing mechanism is mounted at the head of the machine and comprises a bracket 119 fastened rigidly to the upper end of a post 121 that is mounted fast on the machine frame. This twister mechanism, except for features that will be hereinafter mentioned, is like that which has been on the market for many 30 years under the name of the "Acme Twister", and is shown and described in the Ames Patent No. 725,311, granted April 14, 1903. The main or running thread 118 is led from a cop or other source of supply over certain tension and detector mechanisms, not shown, through the twister mechanism, as shown in Figs. 1 and 4, and thence 35 to the thread ring of the machine. A reinforcing thread 117, drawn from a suitable supply, has its advance end normally held in the rotary brush 116 of the twister mechanism. This brush or twister is rotated through suitable connections with a vertical rack bar 115 which is connected at 40 its lower end to the upper end of the link 112. These connections include a shaft 120 and a pinion fast thereon and meshing with the rack 115. When this link is moved 45 downwardly, as above described, it pulls the rack bar 115 downwardly with it, thus rotating the twister 116 and causing it to twist the advance end of the reinforcing thread 117 on to the main thread 118 so that 50 said reinforcing thread will be carried forward with the main thread and knitted into the work.

Pivotaly mounted at 125 upon the head 119 is a slack providing thread guide arm 126 connected by a link 127 with a sleeve 123 which is slidably mounted on the post

121 below the head 119. The rack bar 115 extends loosely through this sleeve and holds it against rotative displacement on the post. This sleeve normally rests on a stud or pin 50 70 124 projecting from the rack bar. Near its outer end the arm 126 carries a thread eye 128 through which the reinforcing thread is led from the bobbin 129. From this eye 128 the thread travels through the twister mechanism, and through the twister brush 116. 75

Normally the slackener 126 occupies an elevated position as shown in Figs. 1 and 4, but when the rack bar 115 is pulled downwardly by the link 112 to twist in the reinforcing thread, the sleeve 123 drops due to 80 its own weight and the weight of the arm 126, thus causing the arm 126 to swing downwardly into a substantially horizontal position. Consequently, at the same time that the advance end of the reinforcing 85 thread 117 is twisted on to the main thread 118 and is carried forward therewith toward the needles, an ample supply of slack thread is provided between the twisted-on end of the reinforcing thread and the supply 90 bobbin to prevent the draft on the thread 117 from pulling said twisted-on end off from the main thread.

When, at the completion of the toe or heel, the rear arm of the lever 156 is swung 95 downwardly, springs 133 and 134 (Fig. 3), connected, respectively, with the levers 107 and 109, swing the latter back to their normal positions again thus lifting the rod 111 and link 112. When link 112 is returned to 100 its normal position it acts through the rack bar 115, stud 124, sleeve 123 and link 127 to swing the slackener 126 upwardly, thereby causing it to draw thread from the bobbin 105 128 to furnish slack for use when the advance end of the reinforcing thread is next twisted in.

The sleeve 123 is also connected by a link 135 with one arm of a bell crank lever 136 fulcrumed on the head 119, the other arm 110 of which is connected by a link 137 with one arm of a second bell crank lever 138 also fulcrumed on the head 119. The other arm of this second bell crank 138 carries at its 115 free end a laterally extending wire finger 139 adapted to engage the reinforcing thread 117. The lever arm on which the finger 139 is mounted actuates a pair of shears or cutters 140 of the usual construction which are mounted on the head 119 just below the brush 116. With this construction it follows that when the sleeve 123 moves downwardly with the rack bar 115 at the start of the toe or heel, said sleeve acts through the link 135, bell crank 136 and link 137 to swing the bell crank 138 in a direction to lift the finger 139 so that it occupies a position above the reinforcing thread 117 while it is being fed forward with the main thread. 120 125 It will be clear, also, that when the sleeve 130

123 is moved upwardly at the completion of the toe or heel, such movement will be transmitted to the bell crank 138 swinging it in a direction opposite to its former movement 5 to cause its wire finger 139 to descend and carry the reinforcing thread between the blades of the cutter 140. At the same time the finger carrying arm operates the movable blade of said cutter and causes it to 10 sever the reinforcing thread.

It is desirable during reciprocating knitting to maintain an increased tension on the thread and a novel mechanism is provided by this invention for automatically increasing and decreasing the tension at the desired times. For this purpose a lever is fulcrumed at 144 on the top of the bracket 119 and comprises two arms 142 and 143, the former resting normally on the upper end 15 of the rod 111, above referred to, and the latter bearing on the upper end of a stem 145 movable vertically within a sleeve 146 rigidly mounted in the head 119. The stem 145 has a disk 130 fixed to its lower end 20 while the sleeve has a cooperating disk or ring 131 fixed thereto. A helical spring 147 located within the sleeve 146 and surrounding the stem 145, engages a head provided on said stem at the upper end thereof 25 and yieldingly urges the disk 130 toward the disk 131. The upper end of the rod 111 is bent laterally, as at 148, Fig. 5, and this laterally extending portion projects under the arm 142. Consequently, when said rod 30 occupies its normal position it holds the arm 143 and stem 145 depressed against the pressure of the spring 147 so that the thread is not gripped by the tension disks 130 and 131. But at the start of the toe and heel 35 when the rod 111 is moved downwardly, as above described, the spring 147 lifts the stem 145 and causes the thread to be yieldingly and frictionally gripped between the disks 130 and 131, thereby increasing the tension on the main thread. This increased tension is maintained during the knitting of the heel and toe but at the completion of these parts the rod 111 is moved upwardly 40 by the spring 133, thus raising the lever arm 142, depressing the stem 145, and lowering the disk 130 into its open position. This relieves the tension previously exerted by 45 this mechanism on the yarn.

The laterally extending upper end portion 50 of the rod 111 also lies beneath the rearward extension of a slack take-up arm 150 secured in a lever 149 mounted on the pivot pin 144 which supports the lever 142-143. This take-up arm 150 extends forwardly and 55 has its end portion bent downwardly and provided with a guide eye through which the thread passes on its way from the twister mechanism to the needles. The rearward extension of this take-up lever or arm is provided with a weight 151 which is operative

when the upper end portion 148 of the rod 111 is moved downwardly away from the rear arm of the lever 150, to swing the lever 150 on its fulcrum in a counter clockwise direction to take up any slack occurring in 70 that stretch of the thread between the twister mechanism and the thread ring. As above stated, the downward movement of the rod 111 is produced at the start of the toe and heel and the rod is held in its lowermost 75 position throughout the knitting of the heel and toe so that during this period the lever 150 is free from the control of the rod 111 and therefore operates to take up the pulsating slackening of the thread occurring 80 during, and due to, reciprocating knitting. When the heel and toe lever 156 is returned to its original position the rod 111 is again raised, thus returning the take-up 150 to its normal position as shown in Fig. 4. 85

In addition to reinforcing the heel and toe of a stocking, it is often desirable also to reinforce the knee, especially of children's stockings, and the present invention provides a simple and reliable mechanism for automatically performing this operation. This mechanism comprises a cam 152, Figs. 2 and 3, which is formed on the hub 153 of the clutch cam 50 and ratchet wheel 43. This cam is arranged to engage one arm of a 90 lever 154 fulcrumed on a stud 155 projecting from the machine frame, the other arm of this lever being drilled to receive a vertical rod or link 157, Fig. 3, carrying a block 158 which is loosely secured to the rod and is 95 swivelly connected at 159 with one arm of the lever 109. A collar 160 is secured to the rod 157 immediately above the end of the lever 154. 100

The pattern chain 35 includes links which 105 operate through the usual controlling mechanism of the machine to impart a step movement to the ratchet wheel 43 after the lower portion of the leg has been formed and when the knee or other portion of the 110 leg which is to be reinforced is to be started. This movement causes the cam 152 to depress the forward arm of the lever 154. The resulting upward movement of the rear arm 115 of the lever 154 acts through the collars 160 and 160', rod 157, lever 109 and link 112 to 115 lower the rack bar 115 and sleeve 123, (Figs. 3, 4 and 6), with the result that the reinforcing thread 117 is twisted on to the main thread 118 and incorporated in the knee portion of the stocking. The cam 152 holds the lever 154 in this position until the reinforced portion of the leg has been nearly completed, whereupon the pattern chain 35 initiates a 120 further movement of the cam 152 to carry it out of engagement with lever. The weight of the larger rear arm of the lever 154 restores it to its normal position, permitting the spring 134 to return the lever 109 to 125 130

its original position and thus cutting out the reinforcing thread, as above described.

It will be observed that the twister 116, slackener 126 and cutter 140 are all actuated through the link 112 while the take-up 150 and the thread tension are both actuated by the link 111. It will also be evident that the link 112 is arranged to be operated either by the heel and toe lever 156 or by the lever 154 but that the link 111 is controlled solely by the heel and toe lever. If the reinforcement of the knee is not desired the thread reinforcement mechanism can be relieved from the control of the cam 152 and lever 154 by loosening the collar 160 and moving it upwardly on the rod 157 out of the range of movement of the lever 154. Similarly, if it is desired to relieve either of the links 111 or 112 and the parts operated thereby from the control of the heel and toe lever, this can readily be done by moving the nuts 113 and 114 from the links 105 and 106, respectively.

It will also be appreciated that the invention has provided an exceedingly simple mechanism for controlling and operating the thread reinforcing means and the associated parts, and that this control has been so far effected through parts of the regular machine that it has been necessary to add only very little additional mechanism.

What is claimed as new is:

1. In a hosiery knitting machine having knitting instrumentalities and pattern mechanism controlling the same whereby the machine is caused to knit automatically a stocking having a foot and leg, the combination of a device for manipulating a reinforcing thread to control its delivery to said instrumentalities, controlling mechanism for causing said device to effect a reinforcement of the stocking during the knitting of the knee portion, and additional controlling mechanism for causing said device to effect a reinforcement of the stocking during the knitting of the heel and toe, said controlling mechanisms being independently operated, whereby either the knee portion or the heel and toe of the stocking, or both, may be reinforced as desired.

50 2. In a hosiery knitting machine having knitting instrumentalities and pattern mechanism controlling the same for causing the machine to knit a stocking automatically, the combination of a device for manipulating 55 a reinforcing thread to control its delivery to said instrumentalities, and two mechanisms for operating said device, both of said mechanisms being under the control of said pattern mechanism and being 60 arranged to be brought into operation by the pattern mechanism independently of each other.

3. In an automatic hosiery knitting machine arranged to knit either rotary or reciprocating work and to change automatically

cally from one of said styles of knitting to the other, the combination of pattern mechanism controlling the sequence of operations of the machine, a lever under the control of said pattern mechanism and operable in effecting a change from rotary to reciprocating knitting, thread reinforcing mechanism, and connections between said lever and said thread reinforcing mechanism for causing said lever to operate the latter mechanism. 75

4. In an automatic hosiery knitting machine arranged to knit either rotary or reciprocating work and to change automatically from one of said styles of knitting to the other, the combination of pattern mechanism controlling the sequence of operations of the machine, a lever under the control of said pattern mechanism and operable in effecting a change from rotary to reciprocating knitting, thread reinforcing mechanism, connections between said lever and said thread reinforcing mechanism for causing said lever to operate the latter mechanism, and additional means under the control of said pattern mechanism for operating said thread reinforcing mechanism.

5. In a knitting machine, a thread reinforcing means comprising a twister mechanism for twisting the reinforcing thread on to the main thread, a reciprocating rack bar for actuating said twister, a slackener for acting on the reinforcing thread to furnish slack substantially at the time said twisting operation is performed, a sleeve through which said rack bar has a limited sliding movement, a cutter for severing the reinforcing thread, means connecting said cutter and slackener with said sleeve, and means for reciprocating said rack bar, whereby the reciprocating of said rack bar acts through said sleeve to operate said cutter and slackener. 95 100 103

6. In a rotary knitting machine for automatically knitting stockings having a heel, toe and leg, the combination of a heel and toe lever, thread guiding means, a takeup for acting on the thread between said means and the work, mechanism for applying tension to the thread, a lever connected with said mechanism, a single device for engaging both said lever and said takeup to operate them, and connections between said heel and toe lever and said device for operating said device automatically.

7. In a rotary knitting machine for automatically knitting stockings having a heel, toe and leg, the combination of thread guiding means, a takeup arm for acting on the thread between said means and the work, mechanism for applying tension to the thread, a lever for acting on said mechanism, a rod having an end portion arranged to act on both said takeup arm and said lever to hold the arm stationary and to 125 130

cause the lever to release the tension exerted by said mechanism on the thread, and automatic means under the control of the pattern mechanism of the machine for operating said rod.

- 5 8. In a knitting machine, a thread reinforcing means comprising a twister mechanism for twisting the reinforcing thread on to the main thread, a reciprocating rack bar 10 for actuating said twister mechanism, a slackener for acting on the reinforcing thread to furnish slack thread substantially at the time that the twisting-on operation is performed, a sleeve having a lost motion 15 connection with said rack bar, a link connecting said sleeve with said slackener, a cutter for severing the reinforcing thread, means connecting said cutter with said sleeve, and mechanism for reciprocating 20 said rack bar comprising a cam arranged to be actuated by the pattern mechanism of the machine.

In testimony whereof we have hereunto signed our names to this specification.
